US0D1059176S

(12) **United States Design Patent** (10) Patent No.: **US D1,059,176 S**
(45) Date of Patent: ** Jan. 28, 2025

(54) **BOTTLE**

(71) Applicant: **PepsiCo, Inc.**, Purchase, NY (US)

(72) Inventors: **Martin Eduardo Broen**, New York, NY (US); **William R. Eaton**, Southbury, CT (US); **Christopher Andrew Gregory**, New York, NY (US); **Niklas Gustafsson**, New York, NY (US); **Stephen Lim**, Chappaqua, NY (US); **Kai Xiang Lin**, Flushing, NY (US); **Qiuchen Peter Zhang**, Mahwah, NJ (US)

(73) Assignee: **PepsiCo, Inc.**, Purchase, NY (US)

(**) Term: **15 Years**

(21) Appl. No.: **29/854,977**

(22) Filed: **Sep. 29, 2022**

Related U.S. Application Data

(63) Continuation of application No. 29/746,755, filed on Aug. 17, 2020, now Pat. No. Des. 965,435.

(57) **CLAIM**

The ornamental design for a bottle as shown and described.

DESCRIPTION

FIG. 1 is a top perspective view of a bottle showing the claimed design;

FIG. 2 is a bottom perspective view thereof;

FIG. 3 is a front view thereof;

FIG. 4 is a left side view thereof;

FIG. 5 is a rear view thereof;

FIG. 6 is a right side view thereof;

FIG. 7 is a top view thereof; and,

FIG. 8 is a bottom view thereof.

The dashed broken lines in the figures show portions of the bottle that form no part of the claimed design.

The dot-dash broken lines in the figures show boundaries that form no part of the claimed design.

1 Claim, 7 Drawing Sheets
